Primary Examiner — Mark A Goodwin(74) *Attorney, Agent, or Firm* — Haynes and Boone, LLP**CLAIM**

The ornamental design for the tie, as shown and described.

DESCRIPTION

FIG. 1 shows a front perspective view of a tie; FIG. 2 shows a top view of the tie of FIG. 1; FIG. 3 shows a bottom view of the tie of FIG. 1; FIG. 4 shows a right side view of the tie of FIG. 1; FIG. 5 shows a left side view of the tie of FIG. 1; FIG. 6 shows a right side view of the unridged and unclaimed area of the tie of FIG. 1; and, FIG. 7 shows the left side view of the ridged tie of FIG. 1. The broken line showing of the ends and central section is included for the purpose of illustrating portions of the tie and forms no part of the claimed design.
